(57) **CLAIM**

The ornamental design for a microscope drape as shown and described.

DESCRIPTION

FIG. 1 is a top, right, front perspective view of a first embodiment of a microscope drape showing my new design; FIG. 2 is a top view of the microscope drape of FIG. 1; FIG. 3 is a bottom view of the microscope drape of FIG. 1; FIG. 4 is a front view of the microscope drape of FIG. 1; FIG. 5 is a back view of the microscope drape of FIG. 1; FIG. 6 is a right side view of the microscope drape of FIG. 1; FIG. 7 is a left side view of the microscope drape of FIG. 1; FIG. 8 is a top, right, front perspective view of a second embodiment of a microscope drape; FIG. 9 is a top view of the microscope drape of FIG. 8; FIG. 10 is a bottom view of the microscope drape of FIG. 8; FIG. 11 is a front view of the microscope drape of FIG. 8; FIG. 12 is a back view of the microscope drape of FIG. 8; FIG. 13 is a right side view of the microscope drape of FIG. 8; FIG. 14 is a left side view of the microscope drape of FIG. 8; FIG. 15 is a top, right, front perspective view of a third embodiment of a microscope drape; FIG. 16 is a top view of the microscope drape of FIG. 15; FIG. 17 is a bottom view of the microscope drape of FIG. 15; FIG. 18 is a front view of the microscope drape of FIG. 15; FIG. 19 is a back view of the microscope drape of FIG. 15; FIG. 20 is a right side view of the microscope drape of FIG. 15; and, FIG. 21 is a left side view of the microscope drape of FIG. 15.

The microscope drape is shown with a symbolic Break in its length. The appearance of any portion of the article between the break lines forms no part of the claimed design.

(Continued)

In the above drawings, the broken lines and the areas within the broken lines form no part of the claimed design.
